UNITED STATES PATENT OFFICE

WILLIAM H. KEY, OF VINELAND, NEW JERSEY, ASSIGNOR TO KIMBLE GLASS COMPANY, OF VINELAND, NEW JERSEY, A CORPORATION OF ILLINOIS

FLAT-TOP SCREW-THREADED VIAL MANUFACTURE

Application filed November 9, 1931. Serial No. 573,763.

Glass vials with screw-threaded necks for the accommodation and attachment in place of threaded closures or caps for the containers have heretofore been made by machinery, 5 as represented by United States Letters Patent 1,437,239, Valversen, Screw neck forming machine, granted November 28, 1922.

Owing, however, to the tools employed in 10 such machines and to their manner of use and cooperation with one another, the end of the neck around the mouth of the vial has seldom, if ever, been sufficiently flat and smooth so that the companion cap would 15 seal the container tight, whereby it could not be used for liquids or powders, although such vials and their caps have heretofore been employed in large quantities for other purposes.

20 I have made such improvements in the tools or implements functioning to produce the threaded necks of such vials that flat-top or plane-end vials can be commercially made on such machine and can, therefore, be employed in the trade for purposes for which 25 vials of this general character have heretofore been unsuited.

In making screw-neck glass vials on the machine of said Letters Patent and incorporating other features of improvement, the 30 screw-threads have extended to the end of the vial neck around the mouth of such receptacle, with the result that during their manufacture some of the soft or molten glass 35 has been squeezed out between the forming tools, thus precluding the production of an absolutely flat top or end of the vial.

My invention, therefore, aims to provide a 40 method and means for manufacturing such vials with flat or plane tops or ends enabling the close-fitting caps to co-act with such surfaces to seal the containers tightly and effectively.

Accordingly, the machine which I employ 45 is substantially like that of said Letters Patent, with the exception of the tools and the shapes of the cams which effect the action of such glass-shaping implements.

From an understanding of what follows 50 it is an easy matter to adapt the patented

machine to work the new tools in the manner indicated hereinafter, and, accordingly, it is deemed unnecessary to duplicate in this patent the mechanism of the earlier patent to which reference is made for the details of 55 construction.

I have found that by using a relatively-flat, nonrotating plunger inside of the heated end of the tubular glass blank from which the vial is to be formed, instead of employing a round, revoluble plunger as disclosed in the patent, the desirable advantage accrues that the plunger or inside-forming element affords an amount of friction on the 60 inside of the vial neck to clear up and polish 65 the glass and to prevent carbon from the oil used on the plunger from settling thereon and making it somewhat rough.

If such carbon finds lodgment on a rotary plunger, the roughness or unevenness caused 70 thereby is cast inside in the vial neck, but the non-rotary plunger, by its scraping or wiping action on the inner surface of the neck, prevents any such carbon from doing 75 harm.

In the patented machine, the groove of the thread-forming roller extends from one 80 end of the roller to its opposite end, the result being that some of the hot glass in such helical groove or channel during the performance of its thread-forming function squeezes out of one end of the groove enough to prevent the top or end of the neck from being perfectly flat.

In my improved machine this detrimental 85 effect is avoided by using a rotary thread-producing die, the spiral-thread groove in which does not reach to that end of the die at the mouth of the vial, and at the same time the neck-forming tool remains in action to hold the soft glass in close contact with the abutment of the plunger which forms the flat mouth or top end of the vial. 90

Thus by using these improvements in co-operation I am enabled to manufacture flat-top, screw-threaded vials with rapidity and economy.

In order to enable those acquainted with this art to understand the invention fully, both from structural and functional stand- 100

points, in the accompanying drawing I have illustrated a present, preferred method and means of forming such vials, the illustration being somewhat diagrammatical but sufficient for the present purpose.

In this drawing:—

Figure 1 shows in elevation the heated end of the tubular glass blank and the three tools in retracted position;

10 Figure 2 is a similar view with the tools advanced, the plunger having entered the open mouth of the blank;

Figure 3 illustrates the next step in the operation, the forming of the neck;

15 Figure 4 reveals the succeeding step which comprises the production of the screw-thread on the exterior of the neck; and

Figure 5 is a perspective view of the plunger or inner tool.

20 The glass tube or blank 10 is supported and rotated by the means presented in the patent referred to, or by any other convenient and appropriate mechanism, and, after the end section of such blank has become

25 sufficiently heated so that the glass is soft, a flat plunger or inside former 11, having an abutment or shoulder 12, is slid into such end of the blank the proper distance by suitable mechanism such as set forth in the

30 patent.

Then the neck-forming tool 13, which has traveled forwardly with the plunger 11, is, by means similar to that illustrated in the patent, moved up to the heated end portion 35 of the blank, and it, in conjunction with the shouldered plunger, fashions or shapes the soft glass of the rotating blank into a suitable neck with a flat top or end, as shown in Figure 3.

40 Thereupon, and while the plunger 11 and the neck-forming tool 13 are both still in engagement with the blank, as specified, the revolute, thread-forming die-roller 14, which was also carried forwardly with the

45 plunger, moves in toward the neck, contacts therewith, and is rotated thereby, so that the groove 15 in the die produces the screw-thread on the outside of the neck, as illustrated in Figure 4.

50 As is clearly depicted, the groove 15 of the die extends to that end of the die-roller 14 nearest the body or main portion of the tubular blank, but such groove ends or terminates short of the other end of the roller, 55 with the result that the screw-thread on the vial neck does not reach to the corresponding end of the vial but continues, nevertheless, to the other end of the neck.

60 By having one end of the groove 15 closed, the hot glass cannot squeeze out of such end, and therefore, cannot interfere with the production and maintenance of a truly flat end for the neck against which the cap may bear.

Also, during the production of the thread 65 on the neck, the tool 13 holds the plastic

glass against the shoulder 12, thereby assuring the flatness of the top in the finished product.

The threaded neck having been formed on the blank, the tools automatically separate and recede to their original position, so that the finished product may be readily removed from the machine.

The invention has been stated in the following claims, but it is to be borne in mind that many more or less minor or radical changes may be incorporated in the preferred mechanism without departure from the heart of the invention and without the loss of any of its substantial advantages.

I claim:

1. In a machine for forming screw-threaded necks on glass-vials, the combination of means to rotate a tubular glass-blank about its axis, means to heat an end section of said blank, a shouldered plunger adapted to enter the heated end of the blank, a neck-forming tool adapted to bear on the exterior of the heated end portion of the blank and form the neck thereon, a rotary screw-thread-forming roller adapted to bear on the outside of the heated neck of the vial to provide the screw-thread thereon, said roller having a spiral thread-forming groove terminating short of the corresponding end of the roller to stop the thread on the vial-neck short of the open-mouth end thereof, and means to slide said plunger into the open heated end of the tubular glass-blank, to advance the neck-forming tool to the heated section of the blank to provide the vial-neck thereon, and to advance the roller into engagement with the heated vial-neck to form the screw-thread thereon, and to retract said plunger, tool and roller from the finished product, the shoulder of said plunger by engagement with the end of the heated blank forming such end flat and at right-angles to the axis of the blank.

2. In a machine for forming screw-threaded necks on glass-vials, the combination of means to rotate a tubular glass-blank about its axis, means to heat an end portion of said blank, a non-circular non-rotatable shouldered plunger adapted to enter the heated end of the blank, a neck-forming tool adapted to bear on the exterior of the heated end portion of the blank and form the neck thereon, a rotary screw-thread-forming roller adapted to bear on the outside of the heated neck of the vial to provide the screw-thread thereon, said roller having a spiral thread-forming groove terminating short of the corresponding end of the roller to stop the thread on the vial-neck short of the open-mouth end thereof, and means to slide said plunger into the open heated end of the tubular glass-blank, to advance the neck-forming tool to the heated section of the blank to provide the vial-neck thereon, and to ad-

vance the roller into engagement with the heated vial-neck to form the screw-thread thereon while the plunger is in the neck and with its shoulder bearing against the end of the neck, and to retract said plunger, tool and roller from the finished product, the shoulder of said plunger by engagement with the end of the heated blank forming such end flat and at right-angles to the axis of the blank.

3. In a machine for forming screw-threaded necks on glass-vials, the combination of means to rotate a tubular glass-blank about its axis, means to heat an end portion of said blank, a non-circular non-rotatable shouldered plunger adapted to enter the heated end of the blank, a non-rotary neck-forming tool adapted to bear on the exterior of the heated end portion of the blank and form the neck thereon, a rotary screw-thread-forming roller adapted to bear on the outside of the heated neck of the vial to provide the screw-thread thereon, said roller having a spiral thread-forming groove terminating short of the corresponding end of the roller to stop the thread on the vial-neck short of the open-mouth end thereof, and means to slide said plunger into the open heated end of the tubular glass-blank, to advance the neck-forming tool to the heated section of the blank to provide the vial-neck thereon, and to advance the roller into engagement with the heated vial-neck to form the screw-thread thereon while the plunger is in the neck and with its shoulder bearing against the end of the neck and while the neck-forming tool is in engagement with the neck, and to retract said plunger, tool and roller from the finished product, the shoulder of said plunger by engagement with the end of the heated blank forming such end flat and at right angles to the axis of the blank.

4. In an appliance for forming screw-threaded necks on glass-vials, the combination of a shouldered plunger adapted to be inserted in the heated open end of a rotating hollow glass-blank so that the blank end will bear against said shoulder, a neck-forming tool movable longitudinally with said plunger and shiftable toward and from said plunger whereby it may be brought to bear on the exterior of the heated end portion of the blank and form the neck thereon, and a revolute screw-thread-forming roller movable longitudinally with said plunger and shiftable toward and from said plunger whereby it may be brought to bear on the outside of the heated neck of the vial to provide the screw-thread thereon, said roller having a spiral thread-forming groove on its periphery terminating short of the corresponding end of the roller to stop the thread produced on the vial-neck short of the open-mouth end thereof, the shoulder

of said plunger by engagement with the end of the heated blank forming such end flat and at right-angles to the axis of the blank.

5. In an appliance for forming screw-threaded necks on glass-vials, the combination of a shouldered plunger adapted to be inserted in the open heated end of a rotating hollow glass-blank so that the end of the blank will bear against said shoulder, a neck-forming tool shiftable toward and from said plunger whereby it may be brought to bear on the exterior of the heated end portion of the blank and form the neck thereon, and a revolute screw-thread-forming roller shiftable toward and from said plunger whereby it may be brought to bear on the outside of the heated neck of the vial to provide the screw-thread thereon, said roller having a spiral thread-forming groove having one end reaching to and open at the corresponding end of the roller and having its other end terminating short of the opposite end of the roller to terminate the thread produced on the vial-neck short of the open-mouth end thereof, the shoulder of said plunger by engagement with the end of the heated blank forming such end flat and at right-angles to the axis of the blank.

6. In an appliance for forming screw-threaded necks on glass-vials, the combination of a flat non-rotatable shouldered plunger adapted to be inserted in the open heated end of a rotating hollow glass-blank so that the end of the glass-blank will bear against said shoulder, a non-rotary neck-forming tool shiftable toward and from said plunger whereby it may be brought to bear on the exterior of the heated end portion of the blank and form the neck thereon, and a revolute screw-thread-forming roller shiftable toward and from said plunger whereby it may be brought to bear on the outside of the heated neck of the vial to provide the screw-thread thereon, said roller having a spiral thread-forming groove having one end reaching to and open at the corresponding end of the roller and having its other end terminating short of the opposite end of the roller to terminate the thread produced on the vial-neck short of the open-mouth end thereof, the shoulder of said plunger by engagement with the end of the heated blank forming such end flat and at right-angles to the axis of the blank.

In witness whereof I have hereunto set my hand.

WILLIAM H. KEY.
